Crosby Hale & Gould

United States Patent Office.

ROBERT D. HAINES, OF CAMBRIDGE, ASSIGNOR TO THE "BOSTON SILVER-GLASS COMPANY," OF BOSTON, MASSACHUSETTS.

Letters Patent No. 91,119, dated June 8, 1869.

IMPROVED SOLID GLASS-WARE MOULD.

The Schedule referred to in these Letters Patent and making part of the same.

To all whom it may concern:

Be it known that I, ROBERT D. HAINES, of Cambridge, in the county of Middlesex, and State of Massachusetts, have invented an Improvement in Solid Glass-Ware Moulds; and I do hereby declare that the following, taken in connection with the drawings which accompany and form part of this specification, is a description of my invention, sufficient to enable those skilled in the art to practise it.

The improvement relates to the construction of that class of moulds for forming glass-ware in which shallow dishes are pressed into shape in a matrix made in the face of a solid metal die.

In the continuous use of such a die, the metal soon becomes so heated that the formed dish will not drop from it readily, and the operation of moulding has to be suspended until the mould has cooled.

In my invention, I make a solid metal die-wheel, with a series of peripheral matrices, and so mount this wheel upon a stand that it can be rotated, to bring each matrix in succession uppermost, or in position for the action of the plunger, the flat face or outer rim of the matrix which is lowermost resting upon the base of the stand, and holding the die stationary during the moulding-operation.

It is this construction that constitutes my invention.

The drawings represent a die embodying the improvement.

A shows a central vertical longitudinal section of it, and

B is a transverse central section of it.

a denotes a solid metal die-wheel, having on one side a gudgeon, b, mounted in a swivelling bearing, c, hung in a standard, d, and on the opposite side a handle, e, projecting through a vertical slot, f, in an upright, g.

In the peripheral face of the die-wheel, I form a series of matrices, h, as seen in the drawings, there being preferably an even number of said matrices, so that each is diametrically opposite to another.

The two standards d g rise from a base-plate, i, upon which is a projection, k, which fits into the outer part of the lowermost matrix h, and serves to hold the die-wheel in position, while the plunger l is operating, to

press the glass into form in the opposite or uppermost matrix.

The operation of the die-wheel is as follows:

The wheel being in position, as seen in the drawing, the "metal," or molten glass to be pressed is put into the upper matrix, the ring m is put in place, and the plunger is then brought down upon the glass; the plunger and matrix imparting the desired form to the glass, as in other similar moulds. The plunger is then raised, and the ring is removed. Then, by taking hold of the handle, the moulder lifts the wheel on its swivelling bearing c, disengages the lower matrix from the projection k, so that the wheel can be rotatively moved on such bearing, and turns the wheel until the next matrix is brought uppermost, when he lets the wheel down again, thereby bringing the projection k into the opposite matrix, so that the wheel will be held stationary during the next moulding-operation, the plunger then operating against the "metal" dropped into the upper mould, and thus the moulding is continued.

The moulded article stays in the mould when the wheel is turned, after the plunger is raised, and drops therefrom when the wheel is a second time moved, and the large body of metal in the wheel, and the interval of time between the use of each mould to form one article, and its again reaching the uppermost position, keeps each mould in readiness for use in its turn, without its ever becoming too much heated for such use in its turn.

By this construction, the moulder can keep constantly at work, and can mould much faster than where he has to use separate or independent moulds, or wait for his moulds to cool.

I claim a solid glass-ware mould, having a series of peripheral matrices, substantially as described.

I also claim, in combination with such mould, the means for bringing each matrix successively into position, and for preventing movement of the mould during the action of the plunger, substantially as described.

ROBERT D. HAINES.
